(57) **CLAIM**

The ornamental design for a bag-in-box, as shown and described.

DESCRIPTION

FIG. 1 is a front perspective view of a bag-in-box showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is top plan view thereof; and,

FIG. 8 is a view illustrating the bag-in-box in an unfolded state.

In the drawings, the broken lines showing portions of a bag-in-box depict environment and form no part of the claim.
